DISPLAY RACK

John Meniges, Sidney, Ohio

Application December 18, 1933, Serial No. 702,909

7 Claims. (Cl. 211—179)

This invention relates to display racks, particularly to racks for displaying floral pieces at funerals, although it can be used for displaying other articles.

5 Undertakers very often are at a loss for means to satisfactorily arrange the floral pieces at funerals. Frequently they do not know until nearly the last minute how many pieces there will be, nor the size and form of the pieces. And 10 finally, they find it necessary to adapt their arrangement of the floral pieces to the surroundings, all of which it is important for them to be able to do quickly and with as little fuss and disturbance as possible.

15 With these points in view, the object of my invention is to provide a rack that can be folded into a compact form, and which can be expanded so as to afford a considerable space for floral pieces of various forms. Another object is to provide 20 a rack that can be made to display the pieces it carries to the best possible advantage, regardless of their number and diversity. A still further object is to provide a rack the structural members of which are small and slender, and therefore inconspicuous, but so arranged that the resulting 25 rack is strong and stable, yet light and easily handled.

In describing the details of my rack I shall refer to the accompanying drawings, in which

30 Fig. 1 is an elevation in perspective of the rack expanded ready to receive a floral display;

Fig. 2 is a detail of construction, particularly showing mechanism for latching it in open position;

35 Fig. 3 is a side elevation showing the rack somewhat less than fully opened, and

Fig. 4 is a perspective view showing it practically fully folded. That is, it is folded, although some of the members are slightly ajar, making the 40 manner of folding somewhat more easily understood.

Referring principally to Fig. 1, the rack consists of a stair-like frame provided with a prop which enables the frame to stand on the floor. The 45 main part of this frame consists of two lazy tongs, so called, united in parallelism by rods 10, and other rods, to be referred to later. Each lazy tong comprises pairs of bars 11, pivotally joined intermediate their ends like the blades of scissors. 50 Then the ends of the bars are pivotally connected, thereby forming series of collapsible parallelograms. The pivots intermediate the ends of the bars 11, indicated at 12, are shoulder rivets formed on the ends of certain of the rods 10. The 55 upper free corners of the parallelograms are

joined with shoulder rivets 13, formed on the ends of the other rods 10. The lower free corners of the parallelograms are joined with ordinary shoulder rivets 14.

Intermediate the pivot rods 10 the horizontal bars 11 carry rods 15, which rods are in the same plane and in parallelism with the pivot rods 13. Thus is formed rectilinear series of planar groups of rods, which when the frame is open and in service are horizontal and adapted to serve as shelves. The open construction of these shelves, that is, the spaces between the rods, are useful in various ways in setting floral pieces thereon. For instance, the ends of "sprays" can be stuck between the rods. "Wreaths" can be set on edge on the shelves, and parts of the wreaths projecting between the rods will help to hold the wreaths in place. In many ways this form of shelf is useful, in addition to such shelves being very light.

The prop previously referred to, comprises two rods 20, the upper end of each rod being secured under the head of a rivet, 13, each rivet being on an end of the same rod 10. These rods 20 are joined at their lower ends by a cross rod 21. These rods run diagonally across opposite parallelograms of the lazy tongs and pass through guides 22 which are secured to the pivots 12 formed on the ends of a common rod 10. See Fig. 2. It is therefore seen that as the lazy tongs are folded to the position shown in Fig. 4 the prop automatically assumes its position among the bars 11, while as the lazy tongs are opened to the position shown in Fig. 1 the prop assumes the position it occupies in Fig. 1, enabling it to support the rack in position with the shelves 30 horizontal.

For the purpose of locking the frame in the position shown in Fig. 1, I provide a pair of pawls 25. These pawls are formed on the ends of a locking bar 26, which bar is carried on the ends 40 of arms 27, one of which arms is pivotally attached to a vertically disposed bar 11 belonging to each lazy tong. When the rack is opened the pawls 25 drop into notches 28 in rods 20, thereby locking the rack in open position. The pawls are 45 caused to drop into the notches by a spring 29. To prevent the lazy tongs opening too far, stop pins 30 are placed in the rods 20 in a position to engage the guides 22 through which the rods slide. A handle 31 is provided with which to operate the 50 locking bar 26. To prevent lifting the locking bar too far stop hooks 32 are riveted to the bar and arranged to engage an adjacent rod 10, thus protecting the spring from excessive extension.

The horizontal bars 11 are shorter than the 55

vertical bars 11, which results in the parallelograms being oblong. Because of this the altitude of the rack is increased relative to the floor space it occupies, thereby increasing its usefulness as a display rack for floral pieces. This disparity in the lengths of the bars 11 echelons the bars 11 when the rack is folded as in Fig. 4, which causes the ensemble to take, or to appear to take less room.

While I have shown and described what I now regard as the best embodiment of my invention I do not wish to limit myself to the particular construction shown, as the scope of my invention is only limited by the appended claims, which are as follows:

15 1. In a display rack, a pair of lazy tongs united in parallelism by rods that serve as pivots for both lazy tongs, other rods supported by bars of said lazy tongs in the same plane and in parallelism with said pivot rods, so as to form rectilinear series of planar groups of rods, a floor engaging prop attached to one of said pivot rods, enabling the ensemble to be stood on the floor with the lazy tongs in a leaning position of such angularity that said planar groups of rods are substantially horizontal, said prop cooperating with a guide carried by one of the lazy tongs which gives the ensemble stability while standing on the floor, said guide enabling the folding of the lazy tongs into a position in which the lazy tong bars are substantially parallel with the prop.

20 2. In a display rack, a pair of lazy tongs united in parallelism by rods that serve as pivots for both lazy tongs, other rods supported by bars of said lazy tongs in the same plane and in parallelism with said pivot rods, so as to form rectilinear series of planar groups of rods, a prop attached to the ensemble enabling said ensemble to be stood on the floor with the lazy tongs in a leaning position of such angularity that said planar groups 25 of rods are substantially horizontal, said prop comprising a rod attached to a free corner of a parallelogram of one of said lazy tongs, and crossing said parallelogram passing through a guide attached to the diagonally opposite free corner of said parallelogram, and a locking mechanism adapted to lock the frame in open position.

25 3. In a display rack, a pair of lazy tongs united in parallelism, said lazy tongs carrying series of planar groups of rods whereby they are united in said parallelism, said groups of rods being adapted to serve as shelves when the rack is supported at such inclination as to make the shelves horizontal, a prop adapted to support the rack at such inclination, means for attaching the prop to the rack, and guide means for the prop enabling said lazy tongs to fold into a position in which all

of the bars of their parallelograms and said prop are in substantial parallelism.

4. In a display rack, a pair of lazy tongs united in parallelism, said lazy tongs carrying series of planar groups of rods whereby they are united in said parallelism, said groups of rods being adapted to serve as shelves when the rack is supported at such inclination as to make the shelves horizontal, a prop adapted to support the rack at such inclination, means for attaching the prop to the rack, guide means for the prop enabling said lazy tongs to fold into a position in which all of the bars of their parallelograms and said prop are in substantial parallelism, and means for locking the rack in its unfolded position.

5. In a display rack, a pair of lazy tongs united in parallelism, said lazy tongs carrying shelves which occupy a horizontal position when the bars of their parallelograms are substantially horizontal and vertical, respectively, a prop connected at spaced points adjacent its upper end, to diagonally opposite free corners of said lazy tongs, and means for holding said prop in such position with reference to the lazy tongs that the ensemble will stand on the floor with the shelves horizontal, said prop being of such length that its lower end engages the floor when the bars of the parallelograms are substantially horizontal and vertical.

6. In a display rack, a pair of lazy tongs united in parallelism, said lazy tongs carrying shelves which occupy a horizontal position when the bars of their parallelograms are horizontal and vertical, respectively, a prop connected at spaced points adjacent its upper end to diagonally opposite free corners of said lazy tongs, means for holding said prop in such position with reference to the lazy tongs that the ensemble will stand on the floor with the shelves horizontal, said prop being of such length that its lower end engages the floor when the bars of the parallelograms are substantially horizontal and vertical, said lazy tongs being collapsible so the bars of their parallelograms are substantially parallel.

7. In a display rack, a pair of lazy tongs united in parallelism, said lazy tongs carrying shelves which occupy a horizontal position when the bars of their parallelograms are horizontal and vertical, respectively, said shelves consisting of planar series of rods between which articles carried by the shelves can partially depend, a floor engaging prop connected to free corners of certain parallelograms, guides carried by opposite free corners through which said prop slides, and means for latching said guides to said prop.

JOHN MENTGES.
